UNITED STATES PATENT OFFICE.

WILLIAM L. SMITH, JR., OF NASHVILLE, TENNESSEE, ASSIGNOR TO MAY HOSIERY MILLS, OF NASHVILLE, TENNESSEE, A CORPORATION OF TENNESSEE.

CAM HEAD FOR KNITTING MACHINES.

Application filed December 31, 1923, Serial No. 683,804. Renewed May 28, 1928.

My said invention relates to a cam head for knitting machines and comprises improved actuating cams for use on knitting machine dials intended particularly for use 5 in connection with machines for knitting stockings complete from top to toe with ribbed tops and plain feet. A cam head of this form is suitable for use in connection with any of the well-known types of dial 10 and cylinder knitting machine but is peculiarly adapted for use in machines of small diameter for knitting children's sizes. The principal object of the invention is to 15 provide needle actuating cams on a cam head which shall operate the needles freely without binding and which shall permit the use of a larger number of needles than can be used on an ordinary head of small size.

Referring to the accompanying drawings, 20 which are made a part hereof and on which similar reference characters indicate similar parts,

Figure 1 is a bottom plan of the cam head of my invention with the cams in withdrawn 25 position,

Figure 2, a similar view with one cam projected,

Figure 3 a perspective of a needle projecting cam and actuating means for positioning it variously with respect to the heads.

Figure 4 is a perspective of a fragment of the dial cam head, and

Figure 5, a perspective of a disk used therewith.

In the drawings reference character 10 indicates a disk which is secure to the ordinary foundation portion 10' of a cam head. This disk has located thereon a combined 35 needle retracting and guard cam 11 so formed as to cooperate with both of the projecting cams in the operation of knitting. The particular device 11 is an improvement on devices hitherto used for the same purpose and cooperates in a desirable 40 manner with the other cams shown but retracting cams and guard cams of various forms, either separate or combined, may be arranged to cooperate with my improved 45 needle-projecting cams for the purpose specified, and my improved guard and needle-retracting cam device can be used 50 to advantage with other needle-projecting cams, if desired.

The needle projecting cams which are an

important feature of my invention consist 55 of two compound cams of which the one indicated at 12 may be the knitting cam and the other at 13 a clearing or cast off cam for clearing the latches preparatory to casting off the work from the needles. Each 60 of these cams is pivoted as indicated at 14 on a pivot extending through the disk 10 which disk may consist of two or more concentric disks fixed together or may be otherwise made up of several parts. Cams 15 65 are pivoted at 16 to the respective cams 12 and 13 forming jointed or "knuckle" cams. The connection between cams 12 or 13 and 70 15 may be made by means of tongues on cams 15 fitting in slots in the cams 12 and 13. The cams 15 have pins 17 projecting up into slots 18 in the disk 10.

The pivot 14 has secured thereto at the opposite (upper) side of disk 10 a rockarm 75 19 with an upwardly projecting pin 20 adapted to be connected to any suitable operating means for moving the needle-projecting cams to the various positions assumed by them in connection with different knitting operations.

It will be seen that as the cams 12 and 13 swing on their pivots cams 15 will be caused to move with them to a certain extent, the movement of the latter cams being, however, different from that of the first by reason 85 of the pin and slot engagement between the cams 15 and disk 10. Difficulty has been found in the making of children's hosiery of the character above referred to in that the angle on the main swing cam when in 90 projected position is so steep that the needles will not ride on it and this difficulty increases as the diameter of the dial (and consequently of the stocking) decreases. With the use of my two piece knuckle cam it will 95 be seen in Figure 2 that the needle can be started out at a much earlier stage in its travel than when the ordinary one-piece cam is used thereby giving it much less steep angle and enabling it to operate freely. With this improved cam it is also possible to use a larger number of needles in a given 100 diameter than with the old style cam since a shorter needle can be used which will allow more slots to be cut in the dial than has heretofore been possible. The cam plate 11 in a preferred form of the invention has flat or low outer parts 21, 21, 21 bounded

internally at 22, 22 by ridges (Fig. 4) the sides of which ridges merge at the ends to form sharp receding edges at 23, 23. An edge at 24 near the opening 25 for removal of damaged needles, also slopes off sharply and tapers toward a point. The ridges adjacent the edges 23 are broadened at the bottom to extend out to the margin of disk 10 and these edges serve to open fully any latches which are only partially open. This function is of use particularly at the casting off side where a brush is placed to open the latches preliminary to the beginning of knitting but often fails to open them fully whereupon the cam completes the operation. The one-piece cam 11 is desirable also in that it is less expensive to manufacture and assemble than those made in several pieces while the wear is less rapid owing to lack of joints and edges for foreign objects to catch on.

An annular disk 26 which should be made of spring steel or other equally durable material lies between the needle-projecting cams and the dial needles as indicated in dotted lines in Figures 1 and 2, said disk having a central opening at 27. The disk is held in place by the dial post and this is true whether the machine be large or small. The utility of the disk or dial plate is not limited to knuckle cams but it is also useful in connection with dial cams of other varieties and in fact the principle may be used wherever there is danger of injury to the needle-butts by engagement thereof with blunt ends or knuckles of cams forming parts of the path for the needle-butts.

The disk 26, which I prefer to call a dial plate, has for its principal purpose to prevent the needles traveling too far in toward the dial cam post whereby the needle-butts might enter the openings or bays between the inside swing cams or the relatively movable parts of the cams and be sheared off. The outer diameter of this plate is such that the needles can be drawn in by the retracting cam far enough to knock over the dial stitches but not far enough to permit the needle-butts to enter the openings between the cams or parts of cams. The plate rests on top of the dial between the lower faces of the inside swing cams and the shanks of the dial needles. When all of the dial needles are retracted their shanks are underneath this plate. The use of a plate such as shown in Figure 5 or an equivalent device is not limited to cams of the specific type shown in the drawings, a device of this character being useful with dial cams of various conformation for the purpose of preventing needle-butts from entering irregularities or recesses in the inner wall of the needle-butt path and being damaged.

The points at which the needle retracting cams emerge into the guard cams cannot

readily be specified with accuracy but in general the needle retracting cam for the knitting side is located approximately at the lower point marked 22 and includes the knock-over point at 28, while the cam at the upper point 22 serves as a needle retracting cam for the casting-off side of the cam head or cam cap. The intermediate portions are guard cams which serve to prevent needles from flying out of the dial when they are free of fabric.

It will be obvious to those skilled in the art that various minor changes may be made in my device without departing from the spirit of my invention and therefore I do not limit myself to what is shown in the drawings and described in the specification but only as indicated in the appended claims.

Having thus fully described my said invention, what I claim as new and desire to secure by Letters Patent, is:

1. A cam head for knitting machines comprising a supporting disk, guard and retracting cams near the periphery of the disk, a needle projecting cam having a needle projecting section pivoted to said disk, and another needle projecting section pivoted to the first, substantially as set forth.

2. A cam head for knitting machines comprising a supporting disk, guard and retracting cams near the periphery of the disk, a needle projecting cam having a needle projecting section pivoted to said disk, and another needle projecting section pivoted to the first said second section extending rearwardly from the first and having a slidable pin and slot connection with the head, substantially as set forth.

3. A cam head for knitting machines comprising a supporting disk, guard and retracting cams near the periphery of the disk and needle projecting cams located at opposite sides from the center of the disk each needle projecting cam having a needle projecting section pivoted to the disk, and a second needle projecting section pivotally connected to the first, substantially as set forth.

4. A cam head for knitting machines comprising a supporting disk, guard and retracting cams near the periphery of the disk and needle projecting cams located at opposite sides from the center of the disk each needle projecting cam having a needle projecting section pivoted to the disk, and a second needle projecting section pivotally connected to the first said second section extending from the first in the direction of rotation of the head and having a slidable guiding connection with the head, substantially as set forth.

5. A two-piece knuckle cam for operating dial knitting needles comprising a needle projecting section pivoted to the cam head, and a needle projecting section pivoted to

- the first-named section arranged to initiate the projecting movement of the needles, substantially as set forth.
6. A cam head for knitting machines comprising oppositely located needle-projecting cams movable into an idle position, and a thin disk covering said cams when in said position said disk lying between the cams and the dial, substantially as set forth.
- 10 7. A knitting machine dial comprising a needle-projecting cam, a retracting cam, and a plate between the needle projecting cam and the dial said plate engaging the needle butts to limit the inward movement of the needles, substantially as set forth.
- 15 8. A knitting machine dial comprising a needle-projecting cam, a retracting cam, and means concentric with the dial post for limiting the inward movement of the needles, substantially as set forth.
- 20 9. A knitting machine dial comprising a needle-projecting cam movable to idle position, and a plate between said cam and the dial concentric with the dial post said plate approximately covering the cam when in idle position, substantially as and for the purpose set forth.
- 25 10. In a knitting machine, a needle projecting cam comprising two needle projecting sections extending along the path of the needles one section initiating the projecting movement of the needles and the other section completing such movement, substantially as set forth.
- 30 35 11. In a knitting machine, a needle projecting cam comprising two needle projecting sections extending along the path of the needles one section initiating the projecting
- movement of the needles and the other section completing such movement, a pivot for connecting the last-named section to a support, and a pivot connecting said sections the two pivots being out of alinement, substantially as set forth.
12. A cam head for knitting machines comprising a supporting disk, needle projecting cams located at opposite sides from the center of the disk each needle projecting cam having a needle-projecting section pivoted to the disk, a second needle-projecting section pivotally connected to the first, and a unitary strip of material surrounding said needle-projecting cams, said strip having integral guard and retractive cams and having a gate for entry and removal of needles, substantially as set forth.
13. A cam head for knitting machines comprising a supporting disk, needle projecting cams located at opposite sides from the center of the disk each needle projecting cam having a needle-projecting section pivoted to the disk, a second needle-projecting section pivotally connected to the first, and a unitary strip of material surrounding said needle-projecting cams, said strip having integral guard and retracting cams and having a gate for entry and removal of needles, there being inclined sharp latch-opening edges on the strip adjacent the needle-projecting cams, substantially as set forth.
- In witness whereof, I have hereunto set my hand at Nashville, Tennessee, this 27th day of December, A. D. nineteen hundred and twenty-three.

WILLIAM L. SMITH, Jr.
